STARTING MECHANISM FOR EXPLOSIVE ENGINES

James L. Yarian, Chicago, Ill., assignor to Montgomery Ward & Co., Incorporated, Chicago, Ill., a corporation of Illinois

Application December 18, 1936, Serial No. 116,635

5 Claims. (Cl. 74—6)

This invention relates to manually-operated starting mechanism for internal combustion engines, and is more particularly concerned with starters of this type designed for incorporation 5 in motors employed for operating washing machines and similar light machinery.

Motors of the type referred to must be compact and occupy relatively small space, due to the necessity for housing the same in the restricted 10 area afforded by the machines with which they are used. It is necessary, therefore, that starting mechanism for these motors also must be compact and simple in order not to cumber the motors with excess parts or otherwise require greater 15 space than that allotted for accommodating the motor.

The present invention contemplates a novel starting mechanism which answers the requirements indicated, and one which is easily incorporated as a unitary part of the engine structure. 20 When thus built into the engine structure the starting mechanism, in the main, is free from exposure and impairment, insures long service and precludes injury to users as the mechanism is 25 operated.

Other objects and advantages will appear as the nature of the improvements is better understood, the invention consisting substantially in the novel construction, combination and arrangement of parts as will be hereinafter fully described, illustrated in the accompanying drawings and pointed out in the appended claims.

The form of the invention herein shown and described is believed to be a preferred embodiment thereof, but it is to be understood that the same is susceptible to change, modification and variation. The present disclosure, therefore, is to be considered as illustrative and not as imposing restriction or limitation on the invention.

40 In the drawings,

Fig. 1 is a side elevation of an internal combustion engine in which is incorporated the herein described starting mechanism;

Fig. 2 is a vertical transverse sectional view of 45 the engine illustrating the gear connections between the operating lever and the crank shaft of the engine; and

Fig. 3 is a detail sectional view, as on the line 3—3, Fig. 1.

50 Referring in detail to the accompanying drawings, the numeral 10 designates the cylinder of an internal combustion engine of the air-cooled type and of a construction designed for driving washing machines and similar light machinery. The crank shaft thereof is designated by the

5 numeral 11, and the cam shaft by the numeral 12. The construction of the engine and its parts forms no part of the present invention, except as the engine structure may be modified for incorporating 10 therein the herein described starting mechanism.

A foot-operated lever 13 is mounted on the outside of the engine casing, as by a stud 14, on which the lever may be rocked, a spring colter pin 15, or its equivalent, serving to hold the lever 10 on the stud. The inner end of the lever 13 is formed to provide a segment gear 16, while the outer end has a toothed contact head 17 to which the foot of the operator may be applied when it is desired to operate the lever.

15 The segment gear 16 engages a pinion 18 that is carried by a bushing 19, said bushing being rotatably mounted on a reduced neck 20 formed on a hub 21 through which the cam shaft 12 projects, said hub having a shoulder 22 against 20 which the inner end of the bushing 19 abuts. At the outer end of the bushing 19 the same is provided with a reduced neck 23. The bushing 19 freely rotates on the neck 20 of the hub 21.

25 On the cam shaft 12, but within the engine casing, is mounted also a gear of larger diameter, designated 24, and said gear 24 meshes with a pinion 25 that is carried by the crank shaft 11. The pinion 25 also is within the engine casing, and the ratio of said gears 24 and 25 is 2 to 1, 30 thus enabling the crank shaft to be turned over at greater speed than the cam shaft. This is conducive to quicker ignition of the explosive charge with a resultant more rapid starting of the engine.

35 A coil spring 26 surrounds the axis of the lever 13 at the outside of the casing, one end thereof being anchored to the exterior of the casing, as at 27, while the other end of said spring 26 is connected to the segment gear 16, as at 28.

40 On the extremity of the cam shaft 12, being the extremity thereof which projects at the exterior of the engine casing, is mounted a cylindrical cap 29, the same being rigidly fastened to the cam shaft 12 by a pin 30. This cap 29 houses 45 a spiral spring 31. The spring 31 is loosely coiled and fits within the cap 29 with just sufficient clearance between the spring and the inner wall of the cap so that when the engine is operating there will be no engagement between the outer surfaces of the coils of the spring and the wall of the cap. One end of the spring 31 is fixedly connected to the neck 23 of the bushing 19, as at 32, so that as the foot lever 13 is depressed the bushing 19 is rotated to expand the spring 31 into 50 55

engagement with the inner wall of the cap 29 and thereby create a binding action between the spring and the cap. In such position of the parts the cam shaft 12 will be rotated and, through the 5 intermediate gears 18, 24 and 25, the crank shaft 11 also will be rotated. The spring 26 controls the movement of the lever 13, and when pressure is removed from the lever it returns to its normal or elevated position, the spring 26 effecting such 10 return.

It will also be understood that on the return movement of the lever 13 to its normal position the binding action of the spring 31 against the inner wall of the cap 29 will be released, and the 15 cap 29 may rotate freely with respect to the spring when the shaft 12 is operating under the power of the engine.

To cushion the return of the lever 13 to normal position under the reactance of the spring 26 after release of pressure from the lever 13, an elastic buffer 32 is employed. This is held 20 on the engine frame by a retaining cup 33, the buffer 32 being in the path of movement of the lever 13 and against which said lever will contact when it moves back to its normal position. Preferably the buffer 32 is formed of rubber.

The bushing 19, the cap 29 and the spring 31 constitute a clutch between the cam shaft 12 and the operating lever 13 which acts to lock 30 the lever in driving relation to said shaft and automatically to interrupt that relation after the engine has been started. As such clutch, the bushing 19 serves as the driving member, the cap 29 as the driven member and the spring 31 as 35 the intermediate coupling member for the driving and driven members. The bushing 19 and the cap 29 are in line with each other, the open end of the cap fitting over the neck 23 of the bushing and thus enclosing also the spring 31 40 so as to protect the latter against injury and accumulations of dirt.

From the foregoing description it will be apparent that to start the engine the lever 13 is depressed to swing the segment gear 16 on its 45 pivot. The engagement of the gear 16 with the pinion 18 rotates the bushing 19 and this will expand the spring 31 into frictional engagement with the cap 29 which, being fixedly connected to the cam shaft 12, will operate the gears 24 50 and 25 so as to turn over the crank shaft 11. If, on the first depression of the lever 13, the explosive charge is not fired, the lever may be returned to its normal raised position and again 55 depressed, and this operation repeated until the charge is fired and the engine is under operation. Because the bushing 19 has free rotation on the cam shaft 12, it is obvious that when the speed of rotation of that shaft has increased to the point where the cap 29 will break its frictional 60 engagement with the spring 31, the cap 29 will overrun the spring 31. Thus, the gripping action of the spring 31 in relation to the cap 29 automatically will be interrupted.

I claim:

1. In starting mechanism of the class described, wherein is embodied a rotatable shaft in coupled relation to the piston of an explosive engine with one of its ends projecting at the exterior of the engine casing, and also including an operating 65 lever pivotally mounted on the engine casing and provided with a segment gear, a toothed driving member carried by said shaft and freely rotatable thereon, said driving member having a reduced neck at one of its ends, said driving member being engaged by the segment gear of said

operating lever, a driven member directly mounted on said shaft in line with said driving member and fixedly connected to said shaft, said driven member being open at one of its ends and tubular in form, the open end of said driven member receiving the neck of said driving member, and means within said tubular driven member connected to the neck of said driving member and serving to connect the driving member to the driven member when said operating lever 10 is depressed.

2. In starting mechanism of the class described, wherein is embodied a rotatable shaft in coupled relation to the piston of an explosive engine with one of its ends projecting at the exterior of the 15 engine casing, and also including an operating lever pivotally mounted on the engine casing and provided with a segment gear, a toothed driving member carried by the projecting end of said shaft and freely rotatable thereon, one end of 20 said driving member being reduced to form a neck, said driving member being engaged by the segment gear of said operating lever, a driven member directly mounted on said shaft in line with said driving member, said driven member being open at one of its ends and tubular in form, the open end of said driven member overlapping the reduced neck of the driving member, and a coil spring within said tubular driven member having one of its ends connected to the reduced 25 neck of the driving member and expansible into engagement with said driven member for connecting the latter to said driving member when said operating lever is depressed.

3. In starting mechanism of the class described, wherein is embodied a rotatable shaft in coupled relation to the piston of an explosive engine with one of its ends projecting at the exterior of the engine casing, and also including an operating 30 lever pivotally mounted on the engine casing and provided with a segment gear, a toothed bushing carried by said shaft and freely rotatable thereon, said bushing being engaged by the segment gear of said operating lever and having a reduced neck at one of its ends, a cap directly mounted 35 on said shaft in line with said bushing and fixedly connected to said shaft, the open end of said cap overlapping and receiving the reduced neck of said bushing and means within said cap connected to said bushing for connecting the latter 40 to said cap when said operating lever is depressed.

4. In starting mechanism of the class described, wherein is embodied a rotatable shaft in coupled relation to the piston of an explosive engine with one of its ends projecting at the exterior of the 45 engine casing, and also including an operating lever pivotally mounted on the engine casing and provided with a segment gear, a toothed bushing carried by the projecting end of said shaft and freely rotatable thereon, said bushing being engaged by the segment gear of said operating lever and having a reduced neck at one of its ends, a cap directly mounted on said shaft in line with 50 said bushing and fixedly connected to said shaft, the open end of said cap being adjacent to said bushing and overlapping the reduced neck of said bushing, and expansible means within said cap connected to said bushing for connecting the latter to said cap when said operating lever is depressed.

5. In starting mechanism of the class described, wherein is embodied a rotatable shaft in coupled relation to the piston of an explosive engine with one of its ends projecting at the exterior of the engine casing, and also including an operating 55 lever pivotally mounted on the engine casing and provided with a segment gear, a toothed bushing carried by the projecting end of said shaft and freely rotatable thereon, said bushing being engaged by the segment gear of said operating lever and having a reduced neck at one of its ends, a cap directly mounted on said shaft in line with 60 said bushing and fixedly connected to said shaft, the open end of said cap being adjacent to said bushing and overlapping the reduced neck of said bushing, and expansible means within said cap connected to said bushing for connecting the latter to said cap when said operating lever is depressed.

lever pivotally mounted on the engine casing and provided with a segment gear, a cap mounted on the outer end of said shaft and having its inner end open, said cap being fixedly connected to said shaft and constituting a driven member, a toothed bushing also carried by the projecting end of said shaft and freely movable thereon, said toothed bushing constituting a driving member and having a reduced neck at its outer end fitting in and received by the inner open end of said cap, said bushing being arranged between said cap and the engine casing for engagement of the teeth thereof by said segment gear, and means within said cap connected to said bushing 5 for connecting the latter to said cap when said operating lever is depressed.

JAMES L. YARIAN.
